DESIGN FOR COMBINED FOLDER AND ARTICLE DISPLAY DEVICE

Henry D. Miller, Reading, Pa., assignor to Berkshire Knitting Mills, Wyomissing, Pa., a corporation of Pennsylvania

Application January 23, 1936, Serial No. 60,740

Term of patent 14 years

To all whom it may concern:

Be it known that I, Henry D. Miller, a citizen of the United States of America, residing at Reading, in the County of Berks and State of Pennsylvania, have invented a new, original, and ornamental Design for a Combined Folder and Article Display Device of which the following is a specification, reference being had to the accompanying drawings forming part thereof.

Figure 1 is a perspective view of a combined folder and article display device showing my new design, the folder being partly open to show the interior thereof;

Fig. 2 is another perspective view of the combined folder and article display device of Fig. 1, and shows the folder as it appears when folded so as to display the outside, and a rear and bottom edge thereof; and

Fig. 3 is a plan view of the combined folder and article display device shown in Figs. 1 and 2, as it appears when completely opened and supported in a horizontal position for the purpose of permitting a full and direct view of the interior thereof.

The combined folder and article display device illustrated comprises inner wrappers having substantially rectangular openings through which appear rectangular shaded panels in Figs. 1 and 3 which represent cellophane covered openings in the hosiery wrappers forming a part of the device, and the line effect within said rectangular panels represents hosiery fabrics and those portions of the stockings in the device that show through the cellophane covered openings.

The said inner wrappers extend into an interior pocket at each of their four corners and the folder has a rectangular central section of a width about equal to the thickness of two pockets close to which are set the two pairs of pockets nearer the fold line of the article.

I claim:

The ornamental design for a combined folder and article display device, substantially as shown and described.

HENRY D. MILLER.
